US00D389915S

United States Patent [19]

Emerson et al.

[11] Patent Number: Des. 389,915

[45] Date of Patent: **Jan. 27, 1998

[54] **IN-LINE DEVICE FOR DRUG DELIVERY AND/OR LASER FIBER OPTIC DELIVERY SYSTEM**

D. 376,204 12/1996 Huculak et al. D24/133
5,136,676 8/1992 Arnett et al. 600/108
5,395,362 3/1995 Sacharoff et al. 606/108

[75] Inventors: **Rick Emerson, San Jose; Kenneth G. Olson, Los Gatos; Steven A. Daniel, Fremont, all of Calif.**

Primary Examiner—Doris Clark
Attorney, Agent, or Firm—Janet Kaiser Castaneda

[73] Assignee: **Eclipse Surgical Technologies, Inc., Sunnyvale, Calif.**

[57] **CLAIM**
The ornamental design for a in-line device for drug delivery and/or laser fiber optic delivery system, as shown.

[**] Term: 14 Years

DESCRIPTION

[21] Appl. No.: **63,102**
[22] Filed: **Nov. 27, 1996**
[51] LOC (6) Cl. **24-02**
[52] U.S. Cl. **D24/144; D24/133**
[58] Field of Search **D24/130, 144, D24/133; 600/108, 136; 606/1-17; 385/47-56, 88, 89, 92**

FIG. 1 is a front, top perspective view of the in-line device for drug delivery and/or laser fiber optic delivery system showing our new design;

FIG. 2 is a side view thereof;

FIG. 3 is a top view thereof;

FIG. 4 is a bottom view thereof;

FIG. 5 is a front view thereof; and,

FIG. 6 is a rear view thereof.
